United States Patent Office.

PETER CHRISTIANSEN, OF ROCHESTER, MINNESOTA.

Letters Patent No. 91,088, dated June 8, 1869.

IMPROVED SASH-BALANCE.

The Schedule referred to in these Letters Patent and making part of the same.

To all whom it may concern:

Be it known that I, PETER CHRISTIANSEN, of Rochester, Olmsted county, and in the State of Minnesota, have invented a new and useful Improvement in the Mode of Hanging Window-Sashes; and I do hereby declare the following to be a full, clear, and exact description of the same, reference being had to the accompanying drawings, making a part of this specification, in which—

Figure 1 is a front elevation.

Figure 2 is a vertical central section on line *x* *x*, fig. 1.

Figure 3 is a front view of the pulley, detached from the window-frame.

The same letters of reference, where employed in the drawings, denote identical parts.

The nature of my invention consists in the construction of a pulley secured to the upper part of a window-frame.

The sheave of the pulley is provided with projections at its periphery, fitting into the links of a chain, which connects the upper and lower sashes.

A lever is pivoted to the pulley, and so constructed that it may serve to prevent the pulley from rotating, and thereby keep the sashes (suspended by the chain passing round the sheave) in any desired position.

To enable others skilled in the art to make and use my invention, I will proceed to describe its operation and construction.

A is a window-frame, and

B and *C* are the upper and lower sashes.

B and *C* are hooks or eyes, to which a chain, *D*, is fastened.

The chain passes over the sheave *E*, said sheave being attached to a frame or block, *F*, firmly secured to the upper part of frame *A* at *A'*.

The sheave *E* is provided with projections *E'* at its periphery, fitting into the links of the chain *D*.

A pin, *F*, projects horizontally from one of the sides of the block *F*, and a lever, *G*, is pivoted to this projection.

A spring, *H*, is fastened to the lower end of the lever *G*, bearing on the block or fastening, and keeping the upper end of the lever *G* pressed against the pulley.

The lever is shaped somewhat like an *S*. Its upper part is prolonged, and extends horizontally through an aperture cut for that purpose in the block, and enters into a recess in the sheave *E* at *E'*.

To the lower end of the lever *G* is attached a cord or chain, *I*, extending far enough downward to be reached with ease from within.

When the operator pulls the cord or chain *I*, the lever will assume a position, as shown in red lines in fig. 3.

The upper part of the lever *G* will be drawn out of the recess in the sheave, and consequently allow the sheave to revolve.

By this operation, I may place the upper and lower sashes in any desired position, and independently of each other.

On the window-sill, I pivot a catch or lock, *K*, which, when turned into a position at right angles with the sash, enters a groove, *K'*, cut for that purpose in the lower sash. In such position it locks the lower sash to the sill, and cannot be withdrawn but from within.

Having thus described my invention,

What I claim, and desire to secure by Letters Patent, is—

The combination of the pulley-block *F*, toothed sheave *E*, spring-lever *G*, and cords or chains *D* and *I*, all constructed and arranged, with relation to the frame and sashes, substantially as described and shown.

In testimony whereof, I have signed my name to this specification, in the presence of two subscribing witnesses.

PETER CHRISTIANSEN.
